(57) **CLAIM**

The ornamental design for an extended wear electrode patch, as substantially shown and described.

DESCRIPTION

FIG. 1 is a perspective view showing an extended wear electrode patch.

FIG. 2 is a top plan view of the extended wear electrode patch.

FIG. 3 is a bottom plan view of the extended wear electrode patch with a liner partially peeled back.

FIG. 4 is a front elevational view of the extended wear electrode patch.

FIG. 5 is a rear elevational view of the extended wear electrode patch.

FIG. 6 is a right elevational view of the extended wear electrode patch.

FIG. 7 is a left elevational view of the extended wear electrode patch; and,

FIG. 8 is a bottom plan view of the extended wear electrode patch.

In all figures, the light stippling forms no part of the claimed design and is intended to indicate the extended wear electrode patch surface. In addition, the broken lines are included for the purpose of illustrating portions of the extended wear electrode patch that form no part of the claimed design.
